DIVISIBLE EGG CARTON

Richard F. Reifers, New Canaan, Conn., and Henry A. Lord, Palmer, Mass., assignors to Diamond National Corporation, New York, N.Y., a corporation of Delaware

Filed Sept. 19, 1962, Ser. No. 71,767

Term of patent 14 years

(Cl. D58—13)

FIG. 1

FIG. 2

FIG. 3

FIG. 4

FIG. 5

FIG. 6

FIG. 1 is a perspective view of the outside of an open divisible egg carton showing our new design;

FIG. 2 is a perspective view of the inside of said carton;

FIG. 3 is a closed front elevational view thereof;

FIG. 4 is an enlarged top plan view thereof;

FIG. 5 is an enlarged end elevational view thereof; and

FIG. 6 is an enlarged cross-sectional view thereof taken on line 6—6 of FIG. 4.

The characteristic feature of our design resides in the distinctive appearance of the pairs of upstanding posts flanking the lower, flat and substantially triangular area therebetween in combination with substantially triangular open area at the hinge line and notched out area between the lids of the carton's segments, as seen, for example, in FIG. 2.

Optional vents on the ends of the lid portion are shown in broken lines.

We claim:

The ornamental design for a divisible egg carton, as shown and described.
